UNITED STATES PATENT OFFICE.

THEODORE C. PROUTY, OF ELGIN, ILLINOIS, ASSIGNOR, BY MESNE ASSIGNMENTS, TO PATENTS HOLDING CORPORATION, OF CHICAGO, ILLINOIS, A CORPORATION OF DELAWARE.

CLUTCH MECHANISM.

Application filed April 14, 1917. Serial No. 162,081.

To all whom it may concern:

Be it known that I, THEODORE C. PROUTY, a citizen of the United States, residing at Elgin, in the county of Kane and State of Illinois, have invented certain new and useful Improvements in a Clutch Mechanism, of which the following is a specification.

This invention relates to improvements in clutch mechanism and has for its object to provide a clutch means which may be readily operated to cease its function as a clutch.

In the accompanying drawing—

Figure 1 is a front elevation of a speedometer, or more especially the odometer mechanism thereof, partly in section, showing my invention applied thereto.

Fig. 2 is a perspective of the tenths indicating wheel and the sleeve member, a portion of the driving shaft being shown as projecting from the latter.

Fig. 3 is an end view of the odometer setting mechanism, a portion of the setting wheel being broken away for clearness.

Fig. 4 is a sectional view along the line 4—4 of Fig. 1 in the direction of the arrows.

Fig. 5 is a perspective of the spring member; and

Fig. 6 is a sectional view taken along the line 6—6 of Fig. 1, as viewed in the direction of the arrows.

In the embodiment shown in the accompanying drawing, I have illustrated my improved mechanism as applied to a vehicle odometer, or mileage indicator, to permit setting or resetting of the trip indicator, although I do not wish to be restricted to the use of my invention in that connection.

The object of this invention, and the invention, will be more fully set forth in the following specification as shown in the accompanying drawing, in which 10 indicates generally a casing of well known construction containing speedometer and odometer mechanism, the latter comprising a series of indicating dials A, known as season indicators, and a second set of dials indicated by B and known as trip indicators. I have shown three of the latter indicated individually as b', b², and b³, being the tenths, units and tens indicator wheels, respectively. In the mechanism shown, so far as this invention is concerned, is a main driven gear 10' secured to the shaft 11 which is journaled

at one point in a suitable bracket bearing 12 and which terminates in the enlarged portion 11^a. I will refer hereafter to the shaft 11 as the driving shaft, it being understood that rotation is transmitted thereto through the medium of gear 10' which acts as a driving member of the odometer and suitable associated mechanism to transmit the rotation of a vehicle wheel, or the like, whose distance of travel is desired. The indicator wheels b', b² and b³ are rotatably mounted upon the sleeve 13 which loosely surrounds the drive shaft 11 and carries a washer 14 to prevent accidental displacement of the wheel b', etc. In the embodiment of my invention shown, as in a majority of such odometers, it is necessary to transmit the rotation of the driving shaft 11 to the tenths indicator b', and which is transmitted in the proper proportion to the successive indicators b² and b³, the former being rotated one division, generally one-tenth of its circumference for each complete rotation of the tenths wheel, and the latter being similarly rotated in proportion by the rotation of the units indicator b². To provide for the driving of the tenths indicator wheel b', I provide the sleeve 15 rotatably mounted upon the enlarged portion 11^a of the drive shaft 11, as shown in Fig. 1. This sleeve 15 is provided with a flanged, or headed, portion 15^a having a plurality of serrations, or teeth, which mesh with surrounding serrations, or teeth, in the flange of the tenths wheel b', (see Figs. 1 to 4), so that rotation of the sleeve 15 will result in rotation of tenths wheel b', as will be obvious. The sleeve 15 is slotted as indicated at 15^b, (see Fig. 2) and fitting within the slot is the up-turned end 16^a of a coiled spring 16, the same being of such size and dimension as to fit within the enlarged bore 15^c of the sleeve 15 (see Fig. 1) and to normally and tightly grip the portion 11^a of the shaft 11. The spring 16 is so constructed and arranged that its other end 16^b, the same being up-turned, lies outside of the end of the sleeve 15, as shown in Fig. 2, from which end project a plurality of fingers 15^d, between a pair of which lies the said up-turned end 16^b of the spring 16 normally spaced from each of the adjacent fingers 15^d, as shown most clearly in Figs. 2 and 6, for example. A peripherally roughened resetting wheel 20 is provided,

the same being capable of manual operation. The setting wheel is provided with a central aperture 20^a, through which project a slight distance the lugs 20^b fitting between the fingers 15^a of the sleeve 15, the lugs 20^b and fingers 15^a being so arranged as to permit a desired amount of play between the setting wheel 20 and the sleeve 15, hereinafter to be described. This setting 10 wheel 20 is retained in engagement with the sleeve member 15 by means of the washer 21 located outside thereof, the washer being retained in position by means of the screw 22 threaded into engagement with the 15 threaded aperture 11^a, of the shaft 11.

In operation, rotation of the drive shaft 11 will be normally transmitted to the sleeve member 15 through the medium of the coiled spring 16 which positively grips the enlarged portion 11^a of the shaft 11 with sufficient friction to transmit its rotation to the sleeve member 15 through the medium of the upturned end 16^a, the spring 16 being so arranged on the shaft 11 with respect 20 to the direction of rotation of the latter, that such rotation has the effect of tightening the spring 16 upon the shaft portion 11^a, thereby increasing frictional contact. When it is desired to set or reset the trip indicator, the setting wheel 20 is rotated in the desired direction, and the functioning thereof is as follows:

Assuming that the setting wheel 20 is rotated in the direction of the arrow in Fig. 35 6, which rotation would have the effect of decreasing the indication of the trip indicator wheels, the adjacent lug 20^b of the wheel 20 will contact with the up-turned end 16^a of the spring 16, the movement of 40 said spring being resisted by its frictional grip on the shaft 11^a and its up-turned end 16^a mounted in the slot 15^b, this rotation of the setting wheel 20 being continued against the resistance of the spring 16. The 45 latter will be sufficiently uncoiled to decrease the frictional grip on the shaft 11^a until the sleeve member 15 is allowed to rotate on said shaft carrying the tenths wheel b' with it until the desired indication or setting is 50 reached. In the event that it is desired to rotate the indicator wheels in the opposite direction, the rotation of the setting wheel 20 is reversed and the frictional grip of the spring member 16 is sufficiently decreased 55 by virtue of the engagement of the up-turned end 16^a of the spring with the slot 15^b of the sleeve member, the latter being rotated by means of the setting wheel 20, through contact of lug 20^b against the fingers 15^a.

In normal driving, as well as in setting and resetting, the transmission of the tenths wheel b' is communicated to the units wheel b² through the medium of the pinion 25 60 co-acting with suitable gearing in the inner

periphery of the indicator wheels, the mechanism, not forming a part of the present invention, being of the form shown and described in my co-pending application, Serial No. 783,070, filed August 5, 1913.

It will be apparent that I have provided a clutch member to insure such normal driving connection between the driving member and a driven member as will permit independent movement of the driven member 75 relative to the driving member through the medium of setting wheels, or other actuating apparatus, even while the driving member is in operation.

In the embodiment shown in the speed- 80 ometer mechanism, it is obvious that where, as is the case in some forms of speedometer, for instance, the Van Sicklen instrument, the rotation of the main driving element, not shown, leading from the vehicle wheel, 85 or the like, is transmitted to the driving gear 10' and shaft 11 through the medium of worms or worm gears, or other gearing mechanism, it will be impossible to set the gear wheels against resistance of such gearing especially if the same were operating to normally rotate the indicator wheels in a direction opposite to that in which it was desired to set them. It will be obvious and apparent that my invention is susceptible of 90 other embodiments, modifications and improvements, and I do not wish to be restricted to the form shown except as defined in the appended claims.

What I claim is:

1. The combination of a driving shaft, a driven member having a sleeve rotatably mounted upon said shaft, a coiled spring mounted on said shaft and frictionally engaging the same and means for rotating 105 said driven member independently of said driving shaft said spring being automatically disengaged from said driving shaft by the operation of said means.

2. The combination of a driving shaft, a 110 driven member having a sleeve rotatably mounted upon said shaft, a coiled spring mounted on said shaft and frictionally engaging the same, said spring being in engagement with said sleeve to rotate the same 115 with said driving shaft, means for rotating said driven member independently of said driving shaft, said means acting to uncoil said spring to permit relative movement of said sleeve with respect to said shaft.

3. In combination, a driving shaft, a driven member having a sleeve rotatably mounted upon said shaft provided with spaced apart finger portions, a spring coiled around said driving shaft and normally frictionally engaging the same, said spring having a portion engaging said sleeve, and a second portion lying between and spaced from said finger portions.

4. In combination, a driving shaft, a 130

- driven member having a sleeve rotatably mounted upon said shaft provided with spaced apart finger portions, a spring coiled around said driving shaft and normally frictionally engaging the same, said spring having a portion engaging said sleeve, a second portion lying between and spaced from said finger portions, and means associated with said sleeve and operable to move the same relative to said driving shaft, said means having a portion interposed between said finger portions of said sleeve and operable to engage the portion of said spring located therebetween to partially uncoil the same.
5. In combination, a driving shaft, a driven member having a sleeve rotatably mounted upon said shaft, said sleeve being slotted and also having projecting finger portions, a spring coiled around and frictionally engaging said shaft, said spring having a portion closely fitting in said slot, a second portion spaced from and located between said finger portions, and an operating member having a portion fitting between said finger portions and operable when moved in one direction to engage the adjacent portion of said spring to partially uncoil the same.
6. The combination of a driving shaft and a driven member having a sleeve rotatably mounted on the shaft, of a clutch spring connected at one end to the sleeve and within the same, being coiled on the shaft and normally in frictional engagement therewith, and means for rotating said driven member independently of said driving shaft and arranged to automatically loosen the grip of said spring when operated.
7. The combination of a driving shaft, a driven member having a sleeve rotatably mounted upon the shaft, a spring clutch member coiled around and frictionally engaging the shaft and within the sleeve to operatively connect the shaft and member, and means to independently operate the driven member and to automatically disengage said spring from said shaft.
8. The combination of a driving shaft, a driven member having a sleeve rotatably mounted upon the shaft, a spring clutch member coiled on the shaft and within the sleeve to operatively connect the shaft and member, and manually operable means to independently operate the driven member and automatically disconnect the operative engagement of the clutch with the shaft.
9. The combination of a driving shaft; a driven member having a sleeve rotatably mounted upon the shaft; a spring clutch member coiled on the shaft and within the sleeve to operatively connect the shaft and member; and manually operable means, con-
- structed and arranged to independently operate said driven member and automatically disconnect the operative engagement between the shaft and spring, and permit relative movement of the sleeve with respect to the shaft.
10. Resetting mechanism for odometers comprising a driving shaft, a driven member having a sleeve provided with longitudinally extending spaced apart fingers rotatably mounted on the shaft, a spring coiled around the shaft and normally frictionally engaging the same, the spring having a portion engaging the sleeve, and a second portion lying between and spaced from the fingers.
11. Resetting mechanism for odometers comprising a driving shaft, a driven member having a sleeve provided with longitudinally extending spaced apart fingers rotatably mounted on the shaft, a spring coiled around the shaft and normally frictionally engaging the same, the spring having a portion engaging the sleeve, and a second portion lying between and spaced from said fingers, and manually operable means to move the sleeve relative to the shaft, said means having a portion interposed between the fingers of the sleeve and operable to engage the portion of the spring located therebetween, to partially uncoil the same.
12. In combination, a driving shaft, a driven member having a sleeve rotatably mounted upon the shaft, the sleeve being slotted and also having axially projecting fingers, connecting means between the sleeve and shaft comprising a spring coiled around and frictionally engaging the shaft, the spring having a portion closely fitting in the slot, a second portion spaced from and located between said fingers, and operating means having a portion fitting between said fingers and operable when moved in one direction to engage the adjacent portion of said spring to partially uncoil the same, the connecting means being constructed and arranged to automatically reconnect the shaft with the sleeve upon release of the operating means.
13. A clutch mechanism which comprises a driving shaft, a driven sleeve member, a spring member arranged to grip said shaft and connected at each end to said sleeve member and arranged to drive said sleeve from said shaft and means for independently driving said sleeve and automatically releasing said spring from said driving shaft.
